(57) CLAIM

The ornamental design for a back of hand finger bag, as shown and described.

DESCRIPTION

FIG. 1 is a perspective view of the back of hand finger bag showing my design on the wearer's hand;

FIG. 2 is a perspective view of the invention of FIG. 1;

FIG. 3 is a top plan view of the invention of FIG. 1;

FIG. 4 is a side elevation view of the invention of FIG. 1;

FIG. 5 is a front end view of the invention of FIG. 1;

FIG. 6 is a bottom plan view of the invention of FIG. 1;

FIG. 7 is a back end view of the invention of FIG. 1; and,

FIG. 8 is a perspective view of the invention of FIG. 1 showing the pocket in an open position.

The broken line showing of environment in FIG. 1 is for illustrative purposes only and forms no part of the claimed design.

The back of hand finger bag is formed in an ornamental shape which makes it attractive for use for wearing on the wearer's hand.
